Dec. 21-1880

UNITED STATES PATENT OFFICE.

WALTER J. GADSBY, OF BOSTON, MASSACHUSETTS, ASSIGNOR TO ROXBURY CARPET COMPANY, OF SAME PLACE.

DESIGN FOR CARPET.

SPECIFICATION forming part of Design No. 12,067, dated December 21, 1880.

Application filed November 6, 1880. Term of patent 3½ years.

To all whom it may concern:

Be it known that I, WALTER J. GADSBY, a subject of the Queen of Great Britain, residing at Boston, in the county of Suffolk and 5 State of Massachusetts, have invented a new and original Design for a Carpet, of which the following is a specification.

The nature of my design is fully shown in the accompanying photographic illustration, 10 forming a part of this specification.

The design is composed of the heptagonal light ground centers A, having the form shown and ornamented with leaves and flowers; the 15 rhomboidal figures B, ornamented with leaves and flowers placed diagonally and alternating with the figures A, and rectangular figures of various sizes, and floral and foliage designs, as shown, arranged between the diagonal rows formed by the figures A B.

I claim—

The design for a carpet, substantially as shown and described.

In testimony whereof I have signed my name to this specification, in the presence of two subscribing witnesses, this 1st day of November, 25 A. D. 1880.

WALTER J. GADSBY.

Witnesses:

THOMAS J. STEARNS,
WILLIAM SCHMIDT.
